UNITED STATES PATENT OFFICE.

FRITZ BALZER, OF MOLINE, ILLINOIS, ASSIGNOR, BY MESNE ASSIGNMENTS, TO TROY LAUNDRY MACHINERY COMPANY, INC., OF DOVER, DELAWARE, A CORPORATION OF DELAWARE.

CENTRIFUGAL EXTRACTOR.

Application filed February 13, 1925. Serial No. 8,891.

The present invention relates to centrifugal extractors.

More particularly the present invention relates to centrifugal machines for extracting moisture from various articles. The invention is particularly useful in connection with the extracting of moisture from laundry articles and will be described with reference to this use. It will be understood as the description proceeds, however, that the invention is of broader application.

Centrifugal machines, particularly those which operate at relatively high speeds, are frequently dangerous to the operator and other nearby persons. An object of the present invention is to provide a centrifugal extractor in which the danger of injury to the operator or to other nearby persons is minimized.

20 A further object is to provide a centrifugal extractor having a protective door, which door must be closed and held closed for an appreciable period of time before starting is fully accomplished.

25 A further object is to provide a centrifugal extractor having an improved door mechanism, which door mechanism must be closed before the whirling action of the extractor is started, and which door mechanism will 30 automatically open only when the extractor has come to rest, or nearly so.

A further object is to provide a centrifugal extractor in which stoppage of the whirling motion may be accomplished rapidly and 35 efficiently.

40 A further object is to provide a centrifugal extractor which may be set into operation conveniently, which will automatically stop its operation after the performance of a pre- 45 determined function, and which will involve a minimum of danger to the operator.

45 A further object is to provide a centrifugal extractor in which danger of injury to the operator is minimized and which will automatically give predetermined signal indications to said operator.

50 A further object is to provide a centrifugal extractor which may be set in operation only when closed and which will automatically cease operation and open communication to the interior thereof after the performance of a predetermined function.

A further object is to provide a centrifugal extractor which will combine ease of starting

and automatic stopping with the possibility 55 of quickly stopping operation and opening communication to the interior of the extractor in case of emergency.

A further object is to provide a centrifugal extractor having a protective closure, which 60 closure must be closed before the whirling action of the extractor can be started, which door will remain closed until caused to open either upon the performance of a predetermined function or upon the deliberate act of 65 the operator.

A further object is to provide a motor 70 driven centrifugal extractor in which the rotor of the motor may have a fixed axis and will perform satisfactorily regardless of the fact that the load in said extractor may be unbalanced.

A further object is to provide a motor 75 driven centrifugal extractor in which the axis of the rotor of said motor is fixed but which will, nevertheless, permit gyrations of the load carrying portions of said extractor.

A further object is to provide a motor 80 driven centrifugal extractor in which the motor may operate as a driving means and breaking means.

A further object is to provide a centrifugal 85 extractor having a driving motor the rotor axis of which is fixed in a vertical position but which will, nevertheless, permit gyrations due to uneven loading.

Further objects will appear as the description proceeds.

Referring to the drawings—

Figure 1 is a view in front elevation, parts 90 being broken away, of one embodiment of the present invention;

Figure 2 is a fragmentary sectional view 95 illustrating a ball bearing arrangement for carrying the movable guard or door used in the extractor shown in Figure 1;

Figure 3 is a top plan view of the structure shown in Figure 1;

Figure 4 is a fragmentary sectional view 100 illustrating certain mechanism cooperatively associated with the revoluble shaft employed in the structure shown in Figure 1;

Figure 5 is a sectional view taken along the plane indicated by the arrows 5—5 of Figure 4, illustrating certain brush holding 105 mechanisms embodied in the present invention;

Figure 6 is a fragmentary view illustrat-

ing mechanism for automatically biasing the extractor door or closure to predetermined position;

5 Figures 7, 8 and 9 are fragmentary views illustrating mechanism for controlling the starting of the centrifugal extractor embodying the principles of the present invention;

10 Figures 10, 10^a, 11 and 12 illustrate mechanism for setting the parts for automatic stoppage of the extractor after the performance of a predetermined function, and for controlling the electrical circuits to accomplish said stoppage;

15 Figure 13 is a wiring diagram illustrating diagrammatically an electric circuit which may be used in the practice of the present invention; and

20 Figures 14 and 15 illustrate a modified construction of speed responsive switch mechanism.

25 Referring first to Figure 1, it will be noted that the curb 10 of a centrifugal extractor is provided with feet 11 by means of which a firm emplacement may be had upon a foundation. Said curb 10 houses the basket 12, which may be provided with the annular ring 13 at its upper portion, leaving said basket open at the top. Said basket is nonrotatably connected to the shaft 14. Said shaft 14 is supported by means of a step bearing assembly, which is indicated as a whole by the numeral 15. Said step bearing assembly constitutes no part of the present invention and need not be described in detail herein. It may be stated briefly, however, that said step bearing assembly compensates for gyrations which may tend to occur in the basket 12 in case said basket is unevenly loaded. Mounted at the upper portion of the curb 10 is the water ring or top ring 16, which may be secured to the curb 10 by means of bolts or other preferred holding means. Said top ring 16 is formed to provide foundations for three columns 17, 18 and 19, which are shown inclined and which may be bolted in position, as best shown in Figure 3. Said three columns are arranged in the back half of the extractor as the parts are viewed in Figures 1 and 3, leaving ample space at the front of the extractor for permitting access to the interior of said extractor. The columns 17, 18 and 19 are secured at their upper ends to the casting 21. Carried at the upper extremity of the casting 21 is the ring 22, which supports the housing of the motor 23. It will be noted that the lower portion of the casting 21 is cored out, whereby to provide a hemispherical surface. Cooperating with the casting 21 is the casting 24, which is also cored out hemispherically. Said castings 21 and 24 are connected by bolts or other holding means to provide a spherical recess adapted to receive a ball-shaped protuberance 25 on the sleeve 26. Said sleeve 26 houses the shaft 14, permitting longitudinal movement of said shaft 14 relative to said

sleeve. Said sleeve 26 extends downwardly a considerable distance in order to provide as long an active bearing as possible.

The present invention contemplates a clutch connection between the rotor shaft of the motor 23 and the shaft 14. A clutch, indicated by the numeral 27, is provided for this purpose. Said clutch includes as one element a friction drum 28 rigidly secured to the upper extremity of the shaft 14, which friction drum 28 will have a cylindrical inner wall. The rotor shaft of the motor 23, which has a fixed axis in a vertical direction, is provided at its lower extremity with a spider-shaped casting 29 having a plurality of radially extending fins 30. Said fins 30 are adapted to ride within recesses in the friction members 31. Said friction members 31-31 are lined upon their peripheral surfaces with some heat resisting material 31^a, such, for example, as raybestos. As indicated in Figure 1, the fins 30 have a very considerable range of oscillatory movement within the recesses in the friction members 31, and the friction members are permitted to move radially of the drum 28. It will be noted that the casting 29 is provided with the collar 31^b, which may be bolted thereto, which collar extends outwardly from the axis of the casting 29 a sufficient distance to prevent the friction members 31-31 from climbing out of the friction drum. When the rotor shaft of the motor 23 is rotating, the fins 30-30 thereof will carry the friction members 31-31 along with them and will permit said friction members 31-31 to fly outwardly under the influence of centrifugal force. Moreover, oscillations of the shaft 14 will be permitted by reason of the fact that a considerable range of oscillation of the fins 30-30 is permitted within their corresponding friction members 31-31. The outer surface of the lining 31^a of the friction members 31 should coincide substantially with the inner periphery of the friction drum 28. When the rotor shaft of the motor 23 is rotating at a predetermined speed, the friction members 31-31 will fly out with sufficient force to establish a driving relation between the rotor shaft of the motor 23 and the friction drum 28, whereby turning movement is communicated to the shaft 14.

105 The centrifugal extractor is a machine the operation of which is likely to be quite hazardous. The present invention contemplates the provision of means whereby the hazard is reduced to a minimum.

110 According to the present invention, the extractor is completely closed in the rear between columns 17 and 19 and columns 18 and 19. The front portion, that is—the part between columns 17 and 19, must be adapted to be opened for permitting loading and unloading. The present invention contemplates 115 means for closing the space between columns 130

17 and 19 and maintaining said closure in closed position during the time that the basket 12 is in motion.

In order to close the space between the 5 columns 17 and 19, the present invention contemplates a closure which may be described as being a portion of a frustrated cone. Said closure, which is indicated by the numeral 32, is provided with the top ring 33 to which 10 the skirt 34 is attached. The top ring 33, as best shown in Figure 2, is provided with means forming a track cooperating with roller bearings 35, which roller bearings are supported from the casting 21. The roller 15 bearings 35 may be carried by studs 36 secured in said casting 21, and said roller bearings may engage the annular member 37, which annular member 37 may be of steel and may be secured to the top ring 33 by any preferred means, as, for example, by means of 20 screws 38. The roller bearings 35 may be shouldered, as indicated by the numeral 39, whereby to bear against the outer side of the track 37 to hold the top ring 33 of the closure 25 32 in coaxial relation with the casting 21. An annular projection 40 may also be provided upon the top ring 34 to keep the roller bearings and the top ring from getting out of 30 their proper relative positions. As noted above, the closure 32 is essentially part of a frustrated cone, that is to say—though said 35 cover has a conical conformation in order to conform to the inclined positions of the columns 17, 18, and 19, part of the wall of the cover 32 is cut away, whereby in a predetermined position of the cover 32 access may 40 readily be had to the basket 12. The open position of the closure 32 is indicated in full lines in Figure 1. The closed position is indicated in dotted lines in Figure 1.

The illustrated embodiment of the present invention is adapted for convenient lubrication. The numeral 41 indicates an oil cup, which supplies oil by means of the pipe 42 to the interior of the casting 21. Oil will flow to the cooperating surfaces of the sleeve 26 and shaft 14 and will also flow to the cooperating surfaces of the ball-shaped protuberance 25 and the spherical housing for said ball-shaped protuberance. It is, of course, necessary to provide means for the disposal of the oil delivered to the surfaces referred to. Attached to the shaft 14 and located beneath the casting 24 is the funnel-shaped casting 43, which is adapted to catch said oil. The shaft 50 14 is provided with a radial hole adapted to communicate with the interior of the funnel-shaped casting 43, which radial hole communicates with an axial hole, indicated by the numeral 44, through which the oil from the funnel-shaped casting 43 is delivered to the bottom of the step bearing 15. Inasmuch as said step bearing 15 is located below the basket 12, there is no danger of the lubricat-

ing oil referred to finding its way into the 65 basket 12.

It will be noted from an inspection of Figures 1 and 2 that the top ring 33 is provided with an annular recess 45. By reason of the recess 45, the top ring 33 operates as a sheave. 70 Mounted within said recess 45 and secured to the top ring 33 is the cable 46 (Figure 3), which may pass over the roller 47. The other end of the cable 46 is provided with a weight 48 (Figure 6), which weight is located 75 in the column 18 at the rear of the extractor. Said weight 48 and cable 46 are arranged to bias the closure 32 to its open position, that is—to the position permitting access to the basket 12. If preferred, the weight 48 may 80 take the form of rollers 49—49, whereby sliding action of the weight 48 within the column 18 will be accomplished with a minimum of friction.

According to certain features of the present 85 invention, the closure 32 is utilized as a medium for controlling the starting of the electric motor 23. Only when said closure 32 is swung to the extreme left, as the parts are 90 viewed in Figure 1, i. e., to closing position, can the control circuits be completed to start the motor and to hold said closure in closed 95 position. According to the present invention, when the machine has completed a predetermined number of revolutions, instrumentalities are actuated to cause the reversal 100 of the motor to produce a braking action upon the rotating basket to bring same to a stop or nearly so, causing the closure 32 to open and causing the open circuiting of said 105 motor. The present invention also contemplates signaling mechanism responsive to the functions of the apparatus, which signaling mechanism will be further referred to.

In order to understand the control circuits 110 above referred to, reference may be had to the wiring diagram shown in Figure 13. As noted above, the closure 32 is biased by the weight 48 to open position. When the operator has loaded the basket 12 and is ready to start operation he will move the closure 32 to the left, that is—to closing position. When 115 said closure 32 has reached closed position, a door switch may be manually operated, which door switch is indicated in the wiring diagram by the numeral 50. Said door switch is biased to open position. Closing of the door switch 50 completes an electrical circuit which energizes the operating coil 51, which operates certain forward contactors of an automatic starter. According to the diagram, starting is accomplished through a resistance, which resistance is cut out after starting has been accomplished. The wiring 120 diagram forms no part of the present invention but may be described briefly in order that the operation may be clearly understood.

According to the wiring diagram shown in

Figure 13, three conductors 52, 53 and 54 are indicated, which conductors constitute the supply mains of an alternating current circuit. It will be understood, of course, that the wiring diagram is merely illustrative of any electrical system that may be chosen and that the invention is not limited to use with alternating current. According to the diagram shown, the closing of the door switch 50 completes a circuit through the operating coil 51 by way of the two conductors 53 and 54, the circuit thus completed being indicated by the letter *a*, which circuit includes the overload relay contacts *a'-a'*. The numerals 55, 56, 57, 58 and 59 indicate switches, of which switches 55, 56, 57 and 58 are biased to open position and of which switch 59 is biased to closed position. Energization of the operating coil 51 will close all of the switches 55, 56, 57 and 58 and will open switch 59. The operation of the switches referred to will connect the three supply mains 52, 53 and 54 to the motor, the circuits thus completed being indicated by the letter *b*. It will be noted that said circuits include the starting resistors 60, 61 and 62. The electric motor 23 will be energized by the completion of the circuits immediately above referred to, said starting being accomplished through the starting resistors 60, 61 and 62. The numeral 63 indicates a switch which is normally open but which is closed when the shaft 14 attains a predetermined speed. The operator must hold the closure 32 in closed position until sufficient speed has been communicated to the shaft 14 to close the switch 63. When said switch 63 is closed, a holding circuit is completed which is independent of the door switch 50. Said holding circuit, which is indicated by the letter *c*, is connected across the terminals of the door switch 50. The circuit *c-c-c* includes the switch 63, the switch 58 which is now closed, the switch 64 which is responsive to the sum total of the number of revolutions of the motor shaft after a predetermined setting, and the switch 65, which is an emergency stop switch, normally closed. The operating coil 51 is now energized independently of the door switch 50. The numeral 66 indicates a latch for holding the closure 32 in closed position. Said latch is controlled by the solenoid 67. When said solenoid 67 is energized the latch 66 is held in a position to maintain the closure 32 in closed position. The circuit of the solenoid 67 is indicated by the letters *d-d-d*, which circuit is connected across the supply mains 53 and 54 through the switch 63. At this time the operator may release his hold on the closure 32, said closure being held in closed position by means of the latch 66, which latch will be operative as long as the switch 63 completes the circuit of the holding solenoid 67.

55 The numeral 68 indicates a time element in-

terlock. Said time element interlock constitutes no part of the present invention, and inasmuch as such interlocks may be readily purchased in the open market no detailed description seems to be necessary. It is sufficient to state that after the lapse of a predetermined period of time said interlock will operate to close the circuit of an operating coil 69, which controls the normally open switches 70, 71, 72 and 73 and the normally closed switch 74. Said time element interlock includes the contact member 75, the control member 76 therefor, and the connector 77. Said contactor 75 is adapted, after the lapse of a predetermined period of time, to contact with the contact member 78 to complete an operative circuit of the operating coil 69.

Operation of the solenoid 69 results in the short circuiting of the starting resistors 60, 61 and 62, whereby the motor 23 may run at full speed.

The present invention contemplates a construction in which the whirling of the basket will be stopped and the closure 32 will be automatically opened upon the occurrence of a predetermined event. According to the mechanism illustrated, the stoppage of the basket and the opening of the closure is accomplished in response to the number of revolutions of the motor shaft. It will be clear as the description proceeds that, if preferred, stoppage of the basket and the opening of the closure may be accomplished in response to any preferred function.

According to the structure illustrated, the details of which will be referred to herein-after, the switch 64 will be opened when the shaft of the motor 23 has made a predetermined number of revolutions, said number being determinable before the starting of said motor. When the switch 64 is opened, the circuit marked by the letters *c-c* is opened, thus deenergizing the operating coil 51. The latch 66 of the closure of the extractor is still held in latching position due to the fact that the switch 63 is still closed.

The open circuiting of the operating solenoid 51 results in the completion of the circuit indicated by the reference characters *f-f*, energizing the contactor solenoid 79. The energization of the solenoid 79 results in the closing of the normally open switches 80, 81, 82 and 83. The energization of the solenoid 79 also results in the opening of the normally closed switch 84. Operation of these switches reverses the connections of the motor 23, whereby said motor will reverse its direction of rotation. It will be obvious, of course, that the change in direction of rotation will not be instantaneous, but that there will be a slowing down of the motor to a stop and a building up of speed in the opposite direction. As the motor slows down, the cooperating elements of the clutch

70

105

110

115

120

125

130

27 will release one another, leaving the basket 12 to rotate by reason of its kinetic energy. Upon the reversal of the motor the friction members 31 will again fly out into engagement with the inner periphery of the friction drum 28, whereby a braking action is exerted upon the shaft 14, bringing the basket 12 to a stop. The stoppage of the basket 12 will cause the switch 63 to open, thereby 5 opening the circuit indicated by the reference characters *c*—*c*, open circuiting the solenoid 79, and also open circuiting the holding coil 67 of the latch 66. The motor is now deenergized, and, inasmuch as the latch 66 10 is biased to unlatching position, the closure 32, which is biased to open position by the weight 48, will automatically open. 15 The numerals 85, 86 and 87 indicate the signaling lights. The letters *g*—*g* indicate 20 the common conductor for the signal lights referred to, which conductor is connected to the main supply conductor 53. When the centrifugal extractor is idle, circuit is completed through the signal light 85, through 25 the conductors indicated by the letters *h*—*h*, to the main supply conductor 54. When the machine is running normally circuit is completed through the signal light 86 by way 30 of the conductors indicated by the reference character *j* to the main supply conductor 54. When the machine is being stopped, that is—when the reverse solenoid 79 is operative to control its corresponding switches, circuit is completed through the light 87 by way of 35 the conductors marked *k* to the main supply conductor 54. The signal lights 85, 86 and 87 may be chosen of different colors. In a practical embodiment of the present invention the signal light 85 indicating an idle 40 condition of the extractor has been chosen as a red light, the light 86 indicating normal running has been chosen as a white light, and the light 87 indicating that the stopping operation is being accomplished has been chosen 45 as a green light.

The mechanical details of the mechanism for putting the extractor in motion and the mechanical details of the mechanism for automatically stopping the extractor will now 50 be referred to.

The switch 63 illustrated in Figures 1 and 4 is a mercury switch comprising a small tube embedded in a disc of insulating material 88'. Said tube is charged with a quantity 55 of mercury and equipped with two contacts 89 and 90, which have electrical connection with the collector rings 91 and 92. Cooperating with the collector rings 91 and 92 are the brushes 93 and 94, which supply 60 current to the slip rings 91 and 92 and consequently to the two terminals of the switch 63.

In view of the fact that the shaft 14 may oscillate about the center of the ball-shaped protuberance 25 of the bearing 26, it is evident 65 that the collector rings 91 and 92 will

not at all times retain their position symmetrical to the vertical axis of the shaft 14. The present invention contemplates means whereby to maintain an uninterrupted flow of electric energy through the brushes 93 and 94 to 70 the rings 91 and 92. To accomplish this purpose the brushes 93 and 94 are mounted upon a carrier 93' (see Figures 1 and 4), which is a yoke loosely carried by the shaft 14. Said yoke preferably is split, whereby it may be 75 conveniently mounted upon said shaft 14. The collar 94', which may be secured to the shaft 14 by any preferred holding means, holds the yoke in its proper position vertically of the shaft 14. The yoke 93', while 80 being loosely mounted upon the shaft 14, is prevented from rotation by reason of the fact that the forks 95—95 of said yoke embrace the rod 96, which is fastened to the upper structure of the extractor and which, 85 while allowing oscillations of the yoke 93' in vertical planes, will prevent rotation of said yoke. It will be noted from an inspection of Figure 5 that the rod 96 is in the form of a tube. Said tube constitutes a conduit 90 for electrical conductors for supplying current to the brushes 93 and 94. It will be evident that when the shaft 14 is rotating at a predetermined speed the switch 63 will be closed. The speed responsive switch 95 described above is a centrifugal switch. The invention is not limited to centrifugal switches, however, and Figures 14 and 15 show the details of a speed responsive switch of another type. 100

Referring to Figures 14 and 15, the numeral 96^a indicates an oil basin corresponding to the funnel-shaped casting 43 of Figures 1 and 4. Said basin 96^a provides a housing for certain switch mechanism, which will now 105 be described, which may be used instead of the centrifugal switch mechanism 63. The switch mechanism shown in Figures 14 and 15 is indicated as a whole by the numeral 96^b. Non-rotatably mounted upon the shaft 14 is 110 the disc 96^c. Carried by said disc 96^c is the disc 96^d, which has no direct connection with the shaft 14. The uppermost disc 96^d is provided with the upstanding slotted lug 96^e and also with the counterbalance 96^f. Mounted 115 on the sleeve 26 is the contact support 96^g, which carries the two relatively stationary contact members 96^h—96^h. Pivotally carried by the contact supporting member 96^g is the swinging member 96ⁱ pivoted for swinging movement about the horizontally disposed pin 96^j. Said swinging member 96ⁱ will be of insulating material, but will carry the bridging contact member 96^k. When the swinging member 96ⁱ is swung to the right as 120 the parts are viewed in Figure 15, connection will be made between the two relatively stationary contacts 96^h—96^h. At other times connection will be broken between said contacts 96^h—96^h. The swinging member 96ⁱ is 125 130

provided near its swinging extremity with the pin 96^l adapted to ride in the vertically disposed slot 96^m in the upstanding stud 96^e carried by the disc 96^a.

5 In operation, when the shaft 14 and consequently the disc 96^e start to rotate, the disc 96^a is dragged around by reason of its frictional engagement with said disc 96^e. It is good practice to permit a certain amount of oil to 10 collect in the bottom of the oil basin 96^a. The viscosity of said oil will also aid in the dragging effect upon the disc 96^a. The disc 96^a is dragged through a sufficient distance to bring the contact member 96^k into bridging 15 relationship with the relatively stationary contacts 96^h—96^h, which will close circuit for operations similar to those described above in connection with speed responsive switch 63. When the shaft 14 and consequently the 20 disc 96^e slow down, the weight of the swinging member 96^a will tend to cause same to assume a vertical position as shown in Figure 15, acting against the frictional resistance between discs 96^e and 96^a and against the 25 viscosity of the oil in the bottom portion of the basin 96^a. Slowing down of the shaft 14 will, therefore, effect the opening of the switch 96^b illustrated in Figures 14 and 15.

The latch assembly for holding the closure 30 32 in closed position will now be described.

Referring to Figures 7, 8 and 9, the door switch 50 is mounted in position to be operated by the handle 97, which handle is rigidly connected to the shaft 98. On the same shaft 35 is mounted a lever 99, which engages the door switch 50 to actuate same. When the handle 97 is turned in a clockwise direction as the parts are viewed in Figure 7, the lever 99 will be caused to engage the door switch 50, pushing 40 same toward the left as the parts are viewed in Figure 7. Movement of the switch 50 toward the left will close said switch, closing the circuit referred to above in connection with the wiring diagram shown in Figure 13. The shaft 98 is biased in a counter-clockwise direction as the parts are viewed in 45 Figure 7 by means of a spring 100, which has one end attached to an abutment fixed relative to the frame of the extractor and which 50 has its other end secured to a finger 101 non-rotatably attached to the shaft 98. Also non-rotatably mounted upon the shaft 98 is the lever 102 (Figure 7), which works in conjunction with the solenoid 67. Cooperation 55 between the lever 102 and the armature of the solenoid 103 is had through the bell crank lever 104, the arm 105 of which is drawn downwardly when the solenoid 103 is energized, said arm 105 being provided with a 60 link 106 connected to the armature of said solenoid 67. The other arm 107 of the bell crank lever 104 is provided with a pin 108 adapted to engage the end of the lever 102. Then the arm 105 is held in its downward 65 position due to the energization of the

solenoid 67, said pin 108 will engage the end lever 102 to hold same downwardly, whereby the shaft 98 and the parts attached thereto will be held against the tension spring 100 in a position to hold the door switch 50 70 toward the left as the parts are viewed in Figure 7, that is—in the position in which said door switch 50 is in circuit closing position.

Also non-rotatably carried by the shaft 98 75 is the finger 109, which has pivotal connection with the longitudinally reciprocable latch 66. Said latch is adapted to enter the hole 111 in the top ring 33 of the closure 32. When said longitudinally reciprocable latch 80 110 is located within the aperture 111, the closure 32 will be held immovably in closed position. The top ring 33 is imperforate throughout its periphery except for the aperture 111. For this reason said top ring will 85 act as an abutment to stop the longitudinal movement of the reciprocable latch 66 at all times, except when said latch 110 is in registry with the aperture 111. By reason of this construction, the handle 97 cannot be 90 moved in a counterclockwise direction to move the door switch 50 to circuit closing position except when the closure 32 is in closed position, that is to say—when said closure 32 is 95 in such a position that the aperture 111 registers with the reciprocable latch 110. When the door switch 50 has been moved to closed position, the motor 23 will be started in the manner discussed above in connection with the description of the wiring diagram appearing 100 in Figure 13. As soon as the spindle 14 of the extractor has reached a speed of rotation sufficiently high to cause the closing of the centrifugal switch 63, the solenoid 67 of the latch assembly shown in Figure 7 will 105 be energized, whereby the shaft 98 and the parts attached thereto will be held against the tension of the spring 100. A material period of time will elapse before the solenoid 67 is energized, which lapse of time will occur 110 while the shaft 14 is accelerating to the speed necessary to close the centrifugal switch 63. An advantage accrues from this fact, inasmuch as the operator must stay at the machine, holding the handle 97 in its counterclockwise direction, until it is evident 115 whether or not the basket 12 is sufficiently well balanced to operate satisfactorily. In order that the operator may see how the basket is operating, the closure 32 may be 120 provided with a transparent portion, not shown on the drawing.

According to the present invention the machine is stopped in response to the action of a revolution counter, which responds to the 125 number of revolutions of the rotor of the driving motor. Such a construction is illustrated for the reason that it has proven satisfactory in service, but other means for accomplishing the same result may be used 130

without departing from the spirit of the invention.

Referring to Figures 1 and 3, the upper element of the clutch 27 is provided with a worm 112 adapted to mesh with a worm gear 113, which communicates rotation to the flexible shaft 114. Said flexible shaft operates the revolution counter, indicated as a whole by the numeral 115 (Figures 10 and 12). Said flexible shaft extends downwardly through the upper portion of the column 19, the revolution counter 115 being carried by and housed within said column 19.

Certain details of the revolution counter 115 and the mechanism responsive to said revolution counter 115 are shown in Figures 10, 11 and 12. The flexible shaft 114 is connected to the worm 116, which worm 116 cooperates with the worm wheel 117 (Figure 12), which worm wheel is omitted from Figure 10 for reasons of clarity.

The revolution counter 115 should be irreversible, and for this purpose the flexible shaft 114 is provided with a spring-controlled one-way clutch. The clutch mechanism forms no part of the present invention, and mechanism suitable for the purpose may be readily purchased. A particular clutch mechanism which has merit and novelty but which is, however, not claimed in this application is illustrated in Figure 10^a. According to said Figure 10^a, two clutching elements 114^a and 114^b are provided, each of said clutching elements having beveled faces. Said clutching elements 114^a and 114^b have cooperating teeth 114^c, which teeth are urged together by the springs 114^d and 114^e. The clutch element 114^a may be connected to the worm gear 113. The clutch element 114^b is connected to the flexible shaft 114. A casing 114^f encloses the clutch elements referred to.

When the worm gear 113 is rotating in a predetermined direction, that is—the normal direction of rotation of the basket 12, the springs 114^a and 114^b will keep the clutch members 114^a and 114^b together; but when the motor reverses, the driven member of the clutch system will not rotate, inasmuch as the clutch member 114^a will slip over the teeth of the clutch member 114^b, being permitted to do so by reason of the beveled faces of the clutch members and the springs 114^d and 114^e.

A timing disc 118 is rigidly connected to the worm wheel 117, said worm wheel 117 and timing disc 118 being loosely mounted upon the spindle 119. Fixedly secured to the shaft 119 is the lever 120, the outer end of said lever being provided with the pin 121. Said pin 121 is provided with a collar 122 and a cylindrical end portion 123 of reduced diameter. The outer end of the shaft 119 has fixedly connected thereto the knurled knob 124, which knob is provided with the indicating finger 125. The cover plate 126 may be pro-

vided with a dial 125' for cooperation with said finger 125, graduated, as preferred; as, for example, in number of revolutions, in minutes if a synchronous motor is used, or according to any other preferred scale.

The numeral 127 indicates a pin fixedly secured to the cover plate 126, which pin provides a rotatable mounting for the trip finger 128. Said trip finger 128 is biased by the spring 129, which tends to push said trip finger 128 in a counterclockwise direction as the parts are viewed in Figure 10. Said trip finger 128 carries the insulating block 129, which carries the contact member 64. An insulating block 131 is stationarily mounted relative to the frame of the extractor, which block 131 carries two contact fingers 132 and 133. Said contact fingers 132 and 133 are adapted to be bridged electrically by the contact member 64. Located between the lever 120 and the cover plate 126 is a spring 134 tending to push the cylindrical end 123 of the pin 121 into one of the apertures 135 of the timer disc 118. In operation the reduced end of the pin 121 will be located in one of the apertures 135 of the timer disc 118. The operator may select the one of the apertures 135 which is to receive the pin 121, his selection depending upon the number of revolutions which are to occur between the starting of rotation and the automatic stoppage thereof. In order to move the index finger 125 to the desired aperture 135, the operator will pull out the knob 124 against the action of the spring 134, thereby removing the reduced end of pin 121 from engagement with the timer disc 118. The operator will then turn the index finger 125 to the mark on the dial 125' corresponding to the point on said dial 125 which indicates the number of revolutions desired before the extractor is automatically stopped. The pull upon the knob 124 may then be released, allowing the reduced end 123 of the pin 121 to seat itself within the desired aperture 135 in the timer disc 118. In the zero position of the index finger 125, the lever 120 and the pin 121 secured thereto will be in a position to hold the trip finger 128 in position to disconnect the contact member 64 from the switch contacts 132 and 133. The setting of the index finger 125 above referred to will free the pin 121 from the trip finger 128, whereby said contact members 132 and 133 will be bridged by the contact member 64. It is evident that after the machine has been stopped, by reason of the fact that the timer disc rotates the lever 120 and pin 121 in a position to throw out the contact member 64, the timing device must be reset to permit the closing of the contact member 64 across the contacts 132 and 133 before operations can be restarted. As explained above in connection with the wiring diagram 113, when the time switch 64 is closed, the circuits of the electric motor 23 130

are changed to produce reverse rotation of the motor 23. As stated above, the inertia of the basket 12 will cause said basket to continue to rotate in its original direction. As the speed of the motor shaft slows down, the clutch 27 will open, and after the motor shaft has come to a stop and has accelerated sufficiently in the opposite direction, the clutch 27 will again be operative, whereby to bring about the quick stoppage of rotation of the shaft 14.

It is, of course, very desirable that rotation of the basket 12 in the reverse direction be avoided. As noted above, the switch 63 is a switch responsive to the speed of rotation of the shaft 14. When the speed of said shaft is zero or nearly so, the switch 63 will open and all of the contactors will revert to the original positions referred to above in connection with the starting of the extractor. At the same time the latch solenoid 67 will be deenergized and the closure 32 will be opened, being moved to open position by reason of the weight 48 located within the column 18.

Attention is directed to the switch 65, which is an emergency stop switch normally closed. Said switch is in series with the stop switch member 64. It will be clear that if for any reason it should be desired to stop the whirling of the basket, as, for example, in the case of a badly loaded basket, the circuits may be opened very quickly by opening said switch 65, whereby the contactors will be returned to original position, just as referred to in connection with the action resulting from the opening of the time switch 64.

It will be noted that the present invention provides an extractor having a driving motor with a vertical shaft whose axis is fixed. Said motor is mounted above the basket containing the articles to be dried. It will be noted also that this desirable mounting of the motor interferes in no way with the action of the basket, which may gyrate in the manner unavoidable in practice under conditions where absolutely even balancing is commercially impracticable.

It will be clear also that the present invention provides a construction in which starting is readily accomplished and which requires the operator to stay by the machine until it is evident whether or not the basket has been badly loaded. The construction is such that the operator is protected from injury by the whirling basket at all times. The present invention also provides automatic stopping mechanism which is positive and simple in its action and which is very little liable to get out of order. Moreover, the present invention provides a construction which permits the quick stopping of the machine in an emergency, as, for example, when the operator has allowed a badly loaded basket to continue its gyrations up to and be-

yond the point at which the centrifugal switch 63 has closed. The present invention also provides a construction by which quick stoppage of the basket is had when such stoppage is required. This feature is important in the saving of time and is of immense importance in case a careless operator has allowed a badly loaded basket to acquire a high speed such that breakage is liable to occur.

The present invention carries with it the advantages of the pilot lights above referred to, which clearly indicate to the foreman and to the operator when the machine is operating normally, when it is inactive, and when stoppage is being accomplished.

Though the preferred embodiment of the present invention has been described in detail, said description should be considered in an illustrative sense rather than in a limiting sense. Many modifications will occur to those skilled in the art. It is intended to cover all such modifications that fall within the scope of the appended claims.

What is claimed is:

1. In a centrifugal extractor, in combination, a motor whose rotor has a fixed axis of rotation, a whirling basket, a centrifugal clutch between said rotor and said basket, and electrical connections for causing the reversal of rotation of said rotor for applying a braking action to said basket.

2. In a centrifugal extractor, in combination, a driving motor, the rotor of which has a fixed axis of rotation, a basket-driving shaft, a clutch between said rotor and said shaft, said clutch having an element attached to said rotor and an element attached to said shaft, friction members adapted to drivingly connect said elements, said shaft being provided with a flexible joint to permit gyrations of said shaft relative to said axis of motor rotation, and electrical means responsive to predetermined functions for causing the reversal of said rotor for applying braking action to said shaft.

3. In combination, a driving shaft having a fixed vertical axis of rotation, a drying basket, centrifugally controlled clutch means between said driving shaft and said basket, means for driving said shaft, and means responsive to the number of revolutions of said motor for reversing the direction of rotation of said driving shaft.

4. In a centrifugal extractor, in combination, a motor having a fixed axis of rotation, a basket-driving shaft subject to gyrations, a universal joint for permitting said gyrations, a centrifugal clutch between said motor and said shaft, and means responsive to the number of revolutions of said motor for changing the direction of motor rotation.

5. In a centrifugal extractor, in combination, a driving motor, a whirling basket adapted to be driven by said motor, a closure

- for said extractor, combined latch and switch means for holding said closure in closed position and for controlling the electric circuit of said motor, means responsive 5 to the speed of rotation of said basket for controlling said combined latch and switch means, and means responsive to the performance of selective functions for controlling said combined latch and switch means.
- 10 6. A centrifugal extractor, including a whirling basket, an electric motor for driving said basket, centrifugal clutch means between said motor and said basket, electric circuits for controlling said motor, means responsive 15 to the performance of predetermined functions for reversing said motor, whereby said motor may through the agency of said centrifugal clutch apply a braking action to said basket, and pilot lights responsive 20 to said electric circuits for indicating the stages of operation of said extractor.
7. A centrifugal extractor, comprising, in combination, a whirling basket, a motor for driving said basket, a closure for said extractor, combined switch and latch means for controlling said closure and said motor, speed responsive means operative only above a pre- 25
- determined basket speed for holding said closure in closed position, and means operative upon the performance of selective predetermined functions for reversing said motor to stop the rotation of said basket and to cause the opening of said closure. 30
8. A centrifugal extractor, comprising, in combination, a whirling basket, a motor for driving said basket, a closure for said extractor, combined switch and latch means for controlling said closure and said motor, speed responsive means operative only above a predetermined basket speed for holding said closure in closed position, and means operative upon the performance of selective predetermined functions for reversing said motor to stop the rotation of said basket and to cause the opening of said closure, said combined 35 switch and latch means being provided with an emergency stop switch by which an operator may manually accomplish the same performance as said reversing means before the completion of said functions. 40
